(57) **CLAIM**

The ornamental design for a golf club holder for ball marker and divot repairer, as shown and described.

DESCRIPTION

FIG. 1 is a top perspective view of my new design for a golf club holder for ball marker and divot repairer;

FIG. 2 is a top plan view of my new invention;

FIG. 3 is a bottom plan view of my new invention;

FIG. 4 is a front elevation view of my new invention;

FIG. 5 is a right side elevation view of my new invention;

FIG. 6 is a left side elevation view of my new invention;

FIG. 7 is a rear elevation view of my new invention; and,

FIG. 8 is a left side elevation view of my new invention in an open mode.

The broken lines indicating are for purposes of illustrating a golf club handle and divot repairer and ball marker and form no part of the claimed design.
